ROLLER SCREEN CONSTRUCTION AND
METHOD

William E. Kemp, Detroit, Mich.

Original application June 22, 1934, Serial No.
731,808. Divided and this application April 11,
1936, Serial No. 73,824

4 Claims. (Cl. 156—25)

The present invention relates to an improved method and means for securing the edge of a sheet of flexible material to a roller upon which it is to be wound.

5 The present application is a division of applicant's copending application Serial No. 731,808, filed June 22, 1934, patented Feb. 8, 1938, No. 2,107,755, which discloses a roller screen construction of the type employed in residences and 10 other structures for the purpose of preventing insects from entering through opened windows, and the present invention is primarily directed to a method and means for connecting wire screening to a cylindrical roller upon which it is to be wound. It is apparent, however, that it is also 15 applicable to the connection of other types of flexible sheet materials to a roller.

It is an object of the present invention to provide a novel means for securing the ends of a 20 flexible strip to a roller and the provision of a spring roller of hollow metallic construction in which the walls of the roller are severed along an axially parallel line, and a roll of flexible material adapted to be rolled upon the roller and having 25 an edge thereof resiliently clamped by the opposed margins of the roll along the lines of split.

Another object of the invention is to provide a novel method of securing a flexible strip of material to a roller.

30 Other objects and advantages of the invention will become apparent from the following specification, the accompanying drawing and the appended claims.

Referring to the drawing wherein like numerals 35 are applied to like parts in the several views:

Figure 1 is a perspective view of a roller having a screen attached thereto in accordance with the present invention.

Figure 2 shows the blank from which the roller 40 is formed.

Figure 3 is a partially broken, partially sectional view of apparatus provided for temporarily expanding the spring roller during the operation of securing the screen thereto, the apparatus being shown in its loading or unloaded position.

Figure 4 is a transverse sectional view taken on the line 4—4 of Figure 3.

Figure 5 is a transverse sectional view corresponding to that shown in Figure 4, but with 50 the parts in the position in which the spring roller is expanded to separate the opposed edges along the split.

Figure 6 is a view similar to Figure 5, but indicating the relative position which the parts assume in order to bend the inner edge of the screen

over against the inside of the roll or tube in order to better insure its being locked in position and to prevent it from interfering with the spring which is ultimately assembled within the roller.

Figure 7 is a fragmentary plan view of the end 5 of the roller shown in Figure 1.

Referring to the drawing there is shown in Figure 1 a tubular roller 66 having a screen 32 secured at its edge thereto and adapted to be rolled upon the roller. Positioned within the end of the 10 roller is a cup-shaped member 70 having a central aperture in which is journaled the shaft 40 of the roller operating mechanism, which is preferably of the type shown in applicant's aforementioned copending application. The outer end of 15 the cup is provided with a split flange 120 overlapping the end of the roller for a purpose to be described.

In the conventional practice, the usual manner of securing the inner ends of screens such as 32 20 to their cooperating roller is to form the roller of a brass tube and to solder the screen thereto. Not only is this a relatively expensive method of securing the screen to the roller because of the length of time necessarily required to effect the 25 soldering operation, but it entails considerable time and labor to place a new screen on the roller and the acid employed in the soldering operation frequently comes in contact with parts of the screen which are exposed during operation and 30 results in unsightly spots thereon. The present invention eliminates the disadvantages of the previous practice in this respect, and moreover provides a construction which may be employed 35 in connecting any flexible strip of material to a roll, regardless of the nature of the flexible strip.

Referring particularly to Figures 2 to 6, inclusive, it will be noted that the body 68 of the roll is split along a line 82 parallel to the axis of the roll. The body 68 is preferably formed in the 40 same manner that butt welded tubing is formed, that is, a suitable length of a strip of metal such as indicated at 84 in Figure 2 is provided and is rolled up into a tube so as to bring opposite longitudinally extending edges into abutting relation 45 with each other, such edges preferably abutting each other with a fair amount of pressure, in the present case preferably between 3 and 6 pounds to the inch in length. In the present instance the ends of the strip 84 are provided with 50 central lugs 86 and edge lugs 88, the purpose of which will hereinafter be more fully described.

In following out the practices of the present invention in securing the screen 32 to the body 68 of the roll 66, the abutting edges along the line 55

82 are caused to be expanded or separated as indicated in Figure 5, the edge of the screen 32 is inserted between the spaced edges, and then the edges are allowed to again contract toward their 5 normal abutting position and in which positions they will then firmly clamp the edge of the screen 32 between them. Preferably, a small amount of the edge is allowed to project into the interior 10 of the body 68 and is bent over in the manner indicated in Figure 6 to further prevent possibility of pulling the screen 32 out of engagement with the body 68. By this means a quick and exceedingly efficient means is provided for securing the screen 32 to the roller.

In order to facilitate expanding of the body 68 to permit the insertion of the end of the screen 32, I preferably employ the apparatus indicated in Figures 3 to 6, inclusive. This apparatus comprises a pair of bar members 90 and 92, each 15 of which is preferably longer than the body 68 and both of which are adapted for simultaneous insertion in a body 68. Opposed faces of the members 90 and 92 are preferably flat to permit them to relatively closely approach each other 20 and the opposite outer faces of the members 90 and 92 are preferably somewhat rounded into conformity with the contour of the inner surface 25 of the body 68. The two members 90 and 92 are connected at intervals by links 94 received within suitable slots 96 provided centrally of the members, the links 94 being pivotally connected at one end by means of pins 98 with the bar 90 and by means of pins 100 with the bar 92. Corresponding ends of the bars 90 and 92 are pivotally 30 connected as by means of pins 102 with a link 104 which is preferably anchored by means of a pin such as 106 to a bracket 108 secured to some fixed 35 surface such as 110. With this construction it will be apparent that if the bars 90 and 92 are pulled in one direction relative to the axial line of the pin 106, as to the left as viewed in Figure 3, and the bars 90 and 92 are maintained in a given (horizontal shown) position during such movement, the links 94 will act to draw the members 40 90 and 92 together or at least to a position of decreased separation. The bars 90 and 92 are so proportioned that when this is done as indicated in Figure 3 the body 68 of the roller 66 may be 45 readily slipped over the bars as indicated in Figure 3. In doing this, the line of split 82 is preferably positioned to the side of the links 94 as illustrated in Figures 2 to 5, inclusive. The bars 90 and 92 with the body 68 thereon are then 50 moved to the right as viewed in Figure 3 to bring the links 104 towards a more vertical position, and during such movement the links 94 act 55 to cause the bars 90 and 92 to separate one from the other. In thus separating from one another the bars 90 and 92 engage opposite faces of the 60 interior of the body member 68 and act to expand the body member, the abutting edges along the line 82 in such case separating from each other to permit such expansion as indicated in Figure 5. When these edges are thus separated 65 from each other the end of the screen 32 is projected between them, after which the mechanism is returned to the position indicated in Figure 3, permitting the abutting edges to again approach each other and to firmly clamp the end of the screen 32 therein. The body 68 with the screen 70 fixed thereto may then be removed from the bars and subsequent operation performed thereon.

Preferably some means are provided for limiting the amount which the end of the screen 32 may be projected between the abutting edges of

the body 68 and such a means is indicated in Figures 4 to 6 as comprising a plate 112 secured in overlapping relation with respect to corresponding side faces of the bars 90 and 92 so as to overlap the space between them. The end of the 5 screen 32 when projected through the space between the separated abutting edges of the body 68 will contact with the plate 112 which will thereby limit further insertion of such end and prevent it from passing between the bars 90 and 10 92. After the bars 90 and 92 are contracted after insertion of the screen 32, the body 68 is preferably rotated relative to the bars 90 and 92, as indicated in Figure 6, so that the inwardly projecting edge portion of the screen 32 will engage 15 one of the bars and be caused to be bent over into contact with the inner face of the body 68. As will be obvious, bending over of the inwardly projecting edge portion of the screen 32 will further enhance the security of the connection of 20 the screen 32 with the body 68.

Although not essential in all cases, it is preferable in order to reduce the amount of physical effort required to expand the body 68 as above described in order to permit insertion of the end 25 of the screen 32, and also to prevent possible distortion of the body 68 longitudinally of the line of severance 82 during the expanding operation, to provide antifriction means between one of the members 90 or 92 and the inner wall of 30 the body 68. Such anti-friction means may be conveniently provided by widening the slot or recess 96 in one of the members 90 or 92, shown as the member 92 in the drawing, to a sufficient extent to permit a roller 114 to be mounted upon 35 each of the pivot pins 100 adjacent the corresponding link 94, the diameter of the roller being such that its periphery projects beyond the outer surface of the member 92. With such a construction the expanding force of the bar 92 40 is transmitted through the rollers 114 which thus serve as anti-friction means to permit relative longitudinal movement between the bar 92 and the body member 68.

It will be apparent that when the blank 84 45 shown in Fig. 2 is rolled into a tube to make the body member 68, the lugs 88 at the same end of the blank will be brought into adjacent relationship so that in the final product each end of the body member 68 will be provided with a pair of 50 approximately diametrically opposed lugs. Now referring to Figures 1 and 7, it will be noted that the outer end of the end member 70 for the roller 66 is provided with a radially outwardly projecting flange 120, against which the corresponding end of the body member 68 abuts. At approximately diametrically opposite points the flange 120 is cut out and in these cut-out portions the lugs 86 and 88 are received, and the outer ends of the lugs are peened over the axially 60 outer face of the flange 120 as at 122 in Figure 7 in order to prevent axial displacement between the end member 70 and the body 68 of the roller 66. Likewise, this engagement of the lugs and the flange 120 locks the end member 70 to the 65 body 68 for equal rotation therewith. As an added feature, it will be noted that the lugs 88 in Figure 2 are preferably tapered on their inner face and the corresponding notch or recess in the flange 120 is preferably so proportioned that, 70 as indicated in Figure 7, when the corresponding end member 70 is forced into the end of the body 68 the sides of the notch will engage the tapered sides of the lugs 88 and will tend to further contract the abutting edges of the body 68 and there- 75

by more firmly clamp the screen 32 therebetween. For this reason one of the notches is preferably held to reasonably close limits and the notches are offset from a true diameter as shown, or 5 otherwise formed so that they will receive the lugs 86—88 in one position only.

Formal changes may be made in the specific embodiment of the invention described without departing from the spirit or substance of the 10 broad invention, the scope of which is commensurate with the appended claims.

What I claim is:

1. In combination, a tubular roller having a line of split extending from end to end thereof, 15 lugs projecting from the ends of said roller on either side of said line of split, a strip of flexible material having a marginal edge thereof clamped between the opposed edges of said roller along said line of split, and end members for said roller 20 engaging said lugs to hold said opposed edges against separation.

2. In combination, a tubular roller having a line of split extending from end to end thereof, a strip of flexible material having a marginal 25 edge thereof received and clamped between the opposed edges of said roller along said line of split, outwardly tapering lugs formed at each end of said roller on either side of said line of split, and end members for said roller having a 30 notched peripheral edge, the lugs at one end of said roller being engaged within the notch of the

corresponding one of said end members and being urged toward one another by the opposite walls of said notch.

3. The method of securing a strip of flexible material to a tubular metallic roller comprising 5 forming a tubular metallic roller with the walls thereof severed along a single line from end to end and so constructed and arranged that the opposed edges of said walls along said line of split are normally in contact with each other, 10 inserting an expanding tool within said tube, expanding said tool so as to cause said opposed edges to be spaced from one another, inserting an edge of said flexible strip between said edges, contracting the expanding tool to permit said opposed 15 edges to engage the edge of said strip, and then rotating said tool and tube relative to each other to cause said tool to engage the inwardly projecting edge of the strip and bend the same against the inner wall of the tube. 20

4. In combination, a tubular roller having a longitudinal split from end to end, a sheet of flexible material having a marginal edge thereof clamped between the opposed edges of said roller at said split therein, the width of said sheet of 25 flexible material being substantially equal to the length of said roller, and means located between the side edges of said sheet of material for holding said opposed edges of said roller against separation. 30
